UNITED STATES PATENT OFFICE.

LAFAYETT L. BARNETT, OF CANTON, MISSOURI.

PICKLE-GRADING MACHINE.

932,749.

Specification of Letters Patent. Patented Aug. 31, 1909.

Application filed November 9, 1908. Serial No. 461,841.

To all whom it may concern:

Be it known that I, LAFAYETT L. BARNETT, a citizen of the United States, residing at Canton, in the county of Lewis and State of Missouri, have invented certain new and useful Improvements in Pickle-Grading Machines; and I do hereby declare the following to be a full, clear, and exact description of the invention, such as will enable others skilled in the art to which it appertains to make and use the same.

This invention relates to machines for grading pickles and other similar material which can be graded according to size; and it consists in the novel construction and combination of the parts hereinafter fully described and claimed.

In the drawings, Figure 1 is a longitudinal section through the machine. Fig. 2 is a plan view of the machine. Fig. 3 is a cross-section through the machine, taken on the line $\alpha-\alpha$ in Fig. 1.

A is the framing of the machine, and B is a receiving hopper for the pickles secured to one end portion of the frame A.

C is a screen which is suspended in the frame in a substantially horizontal position by means of pivoted hangers c, which permit it to oscillate longitudinally. This screen is provided with a series of bars or screening-fingers c'. These bars vary in width step by step, and are widest under the hopper B. The portions of the bars which extend under the hopper are not intended however to screen the pickles.

D are spacing bars carried by the frame A and provided with oblong holes d. Bolts d' provided with nuts for securing them to the bars are adjustable in the slots d laterally of the screen bars, and the lower ends of these bolts are secured to the bars D at suitable intervals in order to support the bars and hold them at the desired distances apart from each other.

E is the driving-shaft of the machine journaled in bearings e secured to the other end of the frame from the hopper. The shaft E is provided with a driving-pulley and fly-wheel e', and it has at its middle part a crank f.

F is a connecting-rod between the crank f and the screen C, so that the said screen is reciprocated longitudinally when the driving-shaft is revolved.

G is a shaft journaled in suitable bearings on the frame in front of and below the

driving-shaft E, and is provided with wheels g. Endless flexible connections H pass over the wheels g and over similar wheels h on a shaft h' at the front end of the machine. 60 The flexible connections H can be chains, cords or any other equivalent devices. Cross-slats I are secured to the endless flexible connections H, and are provided with agitating fingers i having round heads i'. The 65 fingers i are formed of straight metallic pins and their heads are substantially spherical so that they project around the pins in all directions. The round heads of these fingers project upwardly from between the bars of 70 the screen.

A sprocket-wheel K is secured on the shaft G and is driven from a sprocket-wheel k secured on the shaft E by means of a drive-chain k'.

L is a brush which forms the rear end portion of the hopper, and which is adjustable vertically in the frame A, and secured in any desired position by means of any suitable fastening devices b¹.

M are vertical partitions under the screen which form a series of compartments. These compartments are made to correspond in position and number with the stepped portions of the bars of the screen, and they 85 form receptacles for the various grades of pickles. The compartments preferably have their bottoms formed of slats m, and boxes or cans may be slid into the compartments to receive the pickles.

N are endless conveyers mounted on rollers n and n', and extending between the partitions below the screen, and working cross-wise of the screen. The rollers n and n' are mounted in suitable bearings on the frame A, and the driving-roller n has a spiral toothed wheel p secured on its shaft. This wheel p gears into a similar spiral toothed wheel p' secured on the shaft G so that the conveyers N are driven continuously. These 90 conveyers N may however be dispensed with, if desired.

R is a table hinged to the frame below the delivery ends of the conveyers N, and affording a support for cans or boxes into which the graded pickles are discharged by the conveyers.

The pickles are placed in the hopper and are fed out of it, under the adjustable brush, by the agitating fingers i which project from the longitudinal conveyer, between the bars of the screen, and which cause the

pickles to traverse the said screen longitudinally. The small pickles fall through the screen near the hopper where the screen bars are wide, and the various grades of pickles fall through the screen at different parts of its length according to the distance between its bars. The round heads of the fingers prevent the pickles from being defaced, and together with the motion of the screen move the pickles along and turn them about in a manner which insures their being separated into the desired grades.

What I claim is:

In a grading machine, the combination, 15 with a screen having longitudinal bars of different widths at different parts of their length and arranged in the form of steps, of an endless conveyer provided with fingers

which project between the screen bars and which move the material longitudinally over 20 the said bars, partitions arranged crosswise under the said screen and forming a series of compartments for the different grades of material, endless conveyers arranged in the 25 said compartments between the stretches of the aforesaid conveyer and discharging the material at one side of the machine, and driving mechanism for operating all the said conveyers simultaneously.

In testimony whereof I have affixed my 30 signature in the presence of two witnesses.

LAFAYETT L. BARNETT.
